DESK AND MAGAZINE RACK

Edward Waugh Dunning, Baltimore, Md.

Application June 19, 1934, Serial No. 731,353

2 Claims. (Cl. 311—17)

This invention relates to furniture and more particularly to an improved combination desk and magazine rack, one object of the invention being to provide an article of furniture of this character which is so constructed that it will be very compact and occupy a minimum amount of space.

Another object of the invention is to so construct the magazine rack forming the body portion of the device that magazines may be set upright therein and easily inserted or removed from compartments into which they are placed.

A still further object of the invention is to so associate a desk-forming panel or slide with the magazine rack that it may be slid from a horizontal position for use to a vertical position at the back of the rack when not in use where it will be out of the way and concealed from view.

Another object of the invention is to so mount the sliding panel that when extended for use, it will be firmly braced to prevent it from moving out of position for use and to also provide the rack with feet at its back which will prevent the rack from tilting when pressure is applied to the desk-forming slide during use thereof.

Still another object of the invention is to so provide a combination desk and magazine rack which is simple in construction, and capable of being readily transported from one place to another.

With these and numerous other objects in view, my invention consists in the novel features of construction, combination and arrangement of parts as will be hereinafter referred to and more particularly pointed out in the specification and claims.

In the accompanying drawings forming a part of this application:

Figure 1 is a side elevation of the improved desk and magazine rack;

Figure 2 is a front elevation of the desk and rack;

Figure 3 is a sectional view taken along the line 3—3 of Figure 1;

Figure 4 is a vertical sectional view taken along the line 4—4 of Figure 2;

Figure 5 is a sectional view taken along the line 5—5 of Figure 1;

Figure 6 is a view similar to Figure 4 showing the panel extended for use as a desk; and

Figure 7 is a sectional view taken along the line 7—7 of Figure 6.

Figure 8 is a perspective view of the panel.

The body portion of this improved article of furniture constitutes a magazine rack and has a rear wall 1 extending between side walls 2 which

decrease in height towards their forward edges and at their front edges are connected by a short front wall 3. A partition 4 extends vertically between the side walls to divide the body into front and rear compartments 5 and 6 in which magazines are to be set and rest upon the bottoms 7 and 8 of these compartments. Referring to Figures 4 and 6, it will be seen that the bottoms 7 and 8 rest upon supporting strips 9 and 10 where they are secured by nails driven through the partition and front and rear walls. Nails are also employed to secure the partition and walls to each other as shown in Figures 3, 5 and 7. The partition is taller than the front wall but appreciably shorter than the rear wall and, therefore, when magazines are placed in the compartments, their upper portions will project upwardly therefrom in such relation to each other that magazines in the rear compartment will not be concealed by those in the front compartment. This arrangement also permits the magazines to be easily grasped and removed for use.

At the back of the magazine rack, strips 11 are secured vertically against rear edge faces of the side walls and project inwardly therefrom as shown in Figures 3 and 7 to form tracks to receive dowel pins 13 projecting from opposite side edges of a panel 14 which serves as a desk when in the extended horizontal position shown in Figure 6. This panel is of the proper width to fit 30 between the strips 12 and therefore it may be disposed vertically in a retracted position as shown in Figure 4 with its lower end resting upon a cross strip 15 extending between the tracks near the lower ends thereof and its upper portion engaged between the head bar 16 and an abutment bar 17 secured to and extending between the upper portions of the strips 11. The upper portion of the abutment bar is bevelled from its inner face as shown at 18 to provide a sloping 40 surface and allow the panel to be tilted outwardly as it is drawn upwardly and swung to an extended horizontal position in which it rests upon the upper edge face of the abutment bar and has its inner end engaged under the head bar as 45 shown in Figure 6. When in this position, the panel will form a desk.

A finger receiving recess 19 is formed in the panel whereby it may be firmly grasped and slid to a retracted or extended position and the head bar is increased in depth towards its center and formed with a hand receiving opening 20 defining a handle to be grasped when lifting the combined rack and desk and carrying the same from one place to another. When the panel is extended 55

for use as a desk the magazine rack should be braced in order to prevent it from tilting over as weight is applied to the desk during writing and therefore feet 22 are secured against lower 5 end portions of the strips 11 and project rearwardly therefrom. A pencil holder 23 and book rack 24 are secured against the outer face of one side wall and a holder 25 for a pack of cigarettes is secured against the other side wall.

10 When this combination magazine rack and desk is in use, it is set upon a floor against a wall or arm chair or any other location desired with the front of the rack disposed outwardly so that magazines can be inserted or removed from the compartments 5 and 6. The outline of the upper edges of the side walls imparts an attractive appearance to the rack as well as permitting the magazines to be easily grasped and removed from the compartments. When it is desired to use the 15 device as a desk the handle 21 is grasped and the device lifted and moved to a position in front of a chair at such a distance therefrom that the panel may be grasped by its upper end and after being drawn upwardly tilted to a horizontal position in which it rests upon the upper edge of the cross bar 17 with its inner end engaged under the head bar 16. The article of furniture can then be used as a desk in the usual manner and as the feet 22 brace the rack against tilting towards a person, a firm writing surface will be 20 provided. Pencils and pens will be thrust into the sockets 26 of the carrier 23 where they will be supported vertically and can be easily reached and removed when required. It will thus be seen 25 that this article of furniture will be useful either as a magazine rack or desk and will be very attractive in appearance and light in weight so that it can be grasped by its handle and easily moved from one place to another or turned for use as a 30 desk or rack.

35 From the foregoing description of the construction of my improved device, the method of applying the same to use will be readily understood. It will be seen that I have provided a simple, inexpensive and efficient means for carrying out the objects of the invention and while I have particularly described the elements best adapted to perform the functions set forth, it is 40 obvious that various changes in form, proportion

and in the minor details of construction may be resorted to, without departing from the spirit or sacrificing any of the principles of the invention.

Having thus described the invention, what is claimed is:

1. An article of furniture comprising a body having a rear wall and side walls, vertically extending strips carried by the side walls and spaced rearwardly from the rear wall to define tracks at opposite sides of the body, a cross bar extending between said strips adjacent their upper ends and located rearwardly of the tracks, a head bar extending between upper ends of said tracks back of the rear wall in a plane higher than said cross bar and forwardly therefrom, a panel having pins projecting from opposite sides adjacent one end and engaged in said tracks to slidably and tiltably mount the panel for movement from a retracted position to an extended position, said panel when in a retracted position being disposed vertically back of the rear wall with its upper end engaged between the head bar and cross bar and when in an extended position being disposed horizontally and resting upon the cross bar with its inner end engaged under the head bar, abutment means for engaging the lower end of the panel when in its retracted position and supporting the same, and feet projecting rearwardly from lower ends of said strips. 30

2. An article of furniture comprising a body having a rear wall and side walls, strips carried by the side walls and defining tracks at opposite sides of the body back of the rear wall, a cross bar adjacent upper ends of said tracks disposed rearwardly therefrom, a panel having pins projecting from opposite sides adjacent one end and engaged in said tracks to mount the panel for sliding and tilting movement from a retracted vertical position back of the rear wall to an extended horizontal position in which it projects rearwardly from the body and rests upon said cross bar, abutment means to engage over the inner end of the panel when in its extended position, and floor engaging feet projecting rearwardly from lower ends of the strips to brace the body against tilting rearwardly when the panel is in its extended position. 35

EDWARD WAUGH DUNNING.
